UNITED STATES PATENT OFFICE

2,029,897

ELECTRIC IRON

Ludwig Schilling, Poughkeepsie, N. Y.

Application October 22, 1934, Serial No. 749,379

2 Claims. (Cl. 219—23)

While this invention relates primarily to what is known as an electric iron of that class which is employed for pressing clothes and the like, the invention relates more particularly to means for heating the iron without having an electrical heating element embodied in the construction of the iron, and the invention resides in a device comprising an electrical heating device which may be used with one or more pressing and smoothing irons of different shapes and sizes.

In the use of the usual type of electric iron as employed both in factory and domestic use, the iron is provided with an electrical heating element which is built into the iron and which is supplied with electrical current by a drop cord or wires which are attached both to the iron and to a source of current.

With this type of electric iron, it has been found that not only does the drop cord become tangled, quickly worn through which causes shortcircuiting and in many cases starting fires, but that the drop cord gets in the way of the operator and hampers the free use of the iron.

Also with the heating element built into the iron, only one iron may be used at a time, while with my device, several irons may be used, one being heating while the other is in use.

The object of the invention is to provide a device for heating pressing and smoothing irons whereby the iron is not attached by any drop cord and is free and can be moved independently from the heating device.

Another object of the invention is to provide a device whereby the heating apparatus may be placed alongside of the ironing board, thus leaving the board free for use.

Another object of the invention is to provide an automatic heating device, whereby the current is only on and the heating unit energized during the time that the iron is placed thereon, and the electric current is cut off by the removal of the iron.

Another object of the invention is to provide automatic means whereby just as soon as the iron has reached a predetermined temperature, the current will be cut off and a telltale will indicate that the iron is ready for use.

Another object of the invention is to provide a heating device for irons and the like, that is simple, durable, efficient and contains few parts, and which may be manufactured at a low cost.

Another object of the invention is to construct a device of this kind in the form of a complete unit whereby a number of such units may be de-

tachably secured together, side by side, in such a manner that several irons may be heated at the same time, and the electrical current will be carried from unit to unit.

In the drawing:

Figure 1 is a top plan view of the heater or stand without the sad-iron.

Figure 2 is a bottom view of the same, showing the construction and arrangement of the several parts.

Figure 3 shows a longitudinal sectional view of the stand with a sad-iron placed thereon.

Figure 4 shows a number of the stands attached together to accommodate several sad-irons at the same time.

Referring to the drawing:

The heater stand comprises a casting or stamping of suitable material formed with an inclined top 10, sides 11 and 12, and the ends 13 and 14.

The top 10 is formed with an opening within 20 which is mounted the electrical heating element, which is here shown as being of the usual type formed of a molded block of insulating material having about the same outline as that of a sad-iron, and being provided with the grooves or 25 openings 16 within which are mounted the coils of resistance wire 17 which have their ends secured to the terminal posts 18 which extend through the insulating block 19.

Above this heater element 15 are placed the 30 two or more rods or wires 20 upon which the sad-iron rests to keep it from actual contact with the resistance wires.

Adjacent to the bottom or lower edge of the top 10 is placed a rest or stop 21 upon which the 35 rear edge of the sad-iron rests when in place.

The top 10 is also provided with a slot 22 near this stop 21 and within this slot is mounted a depressible switch button 23 of insulating material upon which the heel of the sad-iron rests, 40 depressing the same to close the electrical circuit to the heating element, the circuit being broken upon the removal of the sad-iron from the stand.

Referring to Figure 3 of the drawing, it will be seen that on the under side of the heating element 15 is placed a protective pad of asbestos or other suitable material 24 and over this is placed a cover 25 of insulating material.

As shown in Figure 2 of the drawing, there is mounted upon and in contact with the lower face 50 of the heating element 15 a thermostat 26 which is provided with an arm 27 which has a slight movement in and out as actuated by the thermostat, and the end of this arm 27 is notched and embraces an arm 28 adjacent to its pivot point 55

29; this arm 28 having formed on its outer end a flag 30 which is moved in or out of registry with an opening 31 in the top 10 by the action of the thermostatic operated arm 27 to display through said opening 31 the flag, which may be colored red, when the iron has reached a predetermined degree of temperature, to indicate that the sad-iron is hot and should be removed.

10 The side walls 11 and 12 of the base or stand are provided with male and female elements of an electrical plug 32 and 33; the male plug 32 being adapted to receive the usual plug attached to the drop cord from the current supply, and this male plug 32 is connected to the 15 terminals of the female plug 33 by the wires 34 and 35, and to the switch arm 36 mounted in the top 10, by the wire 37, and to the thermostat by the wire 38; the electrical circuit being completed by the wire 39 to the other terminal of the thermostat.

When it is desired to place a number of these heaters together as shown in Figure 4 of the drawing, it will be seen that the prongs of the male plug 32 will interlock with the prong holes in the female plug 33 of the adjoining heater to both connect the heaters together in a row and also to supply the necessary electrical connection.

In operation, the heater being connected to the 30 electrical current supply and the current turned on, the sad-iron is placed upon the rods 20 with its heel resting against the stop 21 and upon the switch button 23 depressing the button 23 and forcing the switch arm 40 attached to the binding 35 post 18 into contact with the switch arm 41 which is secured to the top 10 to close the electrical circuit to the resistance coil 17, and when the sad-iron has reached the desired degree of tempera-

ture, the thermostat will act to move the tell-tale arm 28 to bring the flag 30 into sight through the opening 31 in the top 10. The removal of the sad-iron allows the button to be raised by the resilient switch arm 40 and opens the electrical circuit to the heating element.

Having thus described my invention, what I claim as new and desire to secure by Letters Patent, is:

1. A sad-iron heating unit comprising a stand for the iron, an electrical heating element mounted in said stand for heating the iron thereon, a current supply means for said heating element and a control therefor operated by the iron, a thermostat mounted in said stand adjacent to the heating element, a tell-tale mounted in said stand, means operated by the thermostat for moving said tell-tale to indicate when the temperature of the heating element has reached a predetermined degree of heat.

2. In a heating stand for irons or the like, a unit base provided with means whereby several of said units can be secured together, an electrical heating element mounted in said stand with its upper face exposed to the iron, a guard thereon adapted to support the iron, a locating stop for the iron, means for feeding electrical current to said heating element, means for controlling said current feed and operated by the iron contacting therewith, a tell-tale mounted in said switch, a thermostat mounted adjacent to the heating element and connected in the current feed, and means operated by said thermostat for moving said tell-tale and cutting off the current supply to the heating element when the heating element has reached a predetermined degree of heat.

LUDWIG SCHILLING.
